GLUING MACHINE

John A. Heckman, Chicago, Ill., assignor to Miller
Wrapping and Sealing Machine Company, Chi-
cago, Ill., a corporation of Illinois

Application January 25, 1940, Serial No. 315,561

16 Claims. (Cl. 91—14)

The machine of the present invention is similar in its general structure to the machine set forth in my co-pending application Serial No. 192,332, filed February 24, 1938, but the present invention is directed primarily to an essentially different method of constructing, mounting and actuating the gluing mechanism provided for the purpose of applying transverse glue lines to an intermittently advancing web of Cellophane, paper, fabric, or the like, all of which materials are included under the term web.

In the machine of the present invention, the glue pot and associated mechanisms are mounted upon a carriage which is intermittently moved back and forth beneath the web during the pauses in its advancement and so constructed as to apply closely spaced parallel glue lines to the web upon each traverse of the carriage, and provision is made for the adjustment of the gluing mechanism so as to permit severing from the web of strips of the desired length by means of a knife which cuts the web transversely between each pair of glue lines, the adjustment being sufficiently accurate to permit such cutting even though the glue lines are spaced closely together.

Provision is also made for adjusting the length of web drawn out during each cycle of operation, and the different adjustments are so co-ordinated as to permit sections of web of the desired length to be severed in such a way as to provide individual wrappers each glued along the edge in close proximity to the line of severance and running transversely of the grain of the web, which is important in the subsequent use of the severed sections for the wrapping of boxes, cartons or the like by suitable wrapping mechanism, which, however, constitutes no portion of the present invention. Provision is also made for adjusting the length of the gluing stroke so that the transverse glue lines will be of the intended length and occupy the intended positions with respect to the web.

The machine embodies mechanism for applying suitably spaced longitudinal glue lines at the desired points and of the desired length, so that the sheets or sections when severed and delivered from the machine will be suitably glued in the desired manner for wrapping purposes.

Further objects and details of the invention will appear from a full description thereof in conjunction with the accompanying drawings, wherein—

Figure 1 is a side elevation of the machine as a whole;

Fig. 2 is a plan view taken on line 2—2 of Fig. 1 with the upper compression roll removed;

Fig. 3 is a sectional elevation taken on line 3—3 of Fig. 2 looking in the direction of the arrows;

Fig. 4 is a section taken on line 4—4 of Fig. 2 looking in the direction of the arrows;

Fig. 5 is a diagrammatic perspective detail showing the transparent web advancing, with the glue lines applied thereto;

Figs. 6 and 7 are similar views showing the web standing stationary, and with the transverse gluing rolls traversing the web first in one direction and then in the other;

Fig. 8 is an enlarged sectional plan view of the glue pot and gluing rolls taken on line 8—8 of Fig. 4;

Fig. 9 is a sectional plan view of the same taken on line 9—9 of Fig. 8;

Fig. 10 is a view of the frame which carries the gluing rolls taken on line 10—10 of Fig. 8;

Fig. 11 is a detail showing a modified form of mechanism for actuating the gluing mechanism for applying the longitudinal glue lines;

Figs. 12 and 13 are sectional details of the presser roll adjustment; and

Fig. 14 is a sectional detail of the carriage trip.

The machine as a whole is built within a frame comprising upper side rails 20 which carry a sub-frame 20* at the forward end, the sides of which are connected by cross guide rods 21 and 22 and by an inverted T-bar 23, and farther to the rear by a cross bar 100, all of which connecting portions constitute functioning elements in the machine combination. Additional cross connections may be provided, if necessary, to afford the required rigidity.

The frame is supported at its four corners upon legs 25 mounting casters 26, which permit the machine as a whole to be easily moved as occasion may require. The legs on each side are connected near their lower ends by lower side rails 27 each of which affords a point of connection for the lower end of an upright bar 28 extending up to and connecting with the upper side rail 20 on the same side of the machine. The lower rail 27 provides support for a platform 29 on which is mounted a motor 30 which drives a pulley wheel 31 by means of a belt 32. The pulley wheel is mounted on a shaft 33 carrying a pinion 34 meshing with a spur gear 35, which arrangement provides a reducing train, thus enabling the spur gear to act as the driving center for the mechanism presently to be described.

The gear 35 is provided with a crank arm 36 which is pivoted to the lower end of a rocker arm 37 carried by a rock shaft 38 upon which is rigidly mounted an upper oscillating bar 39 which carries a rack bar 40 provided on its outer upper edge with rack teeth 41. The rack bar connects with a head 42 which is adjustable upon the upper oscillating bar 39 to vary the stroke 60 of the rack bar which is the active element in

advancing the web to the desired extent during each forward thrust of the rack bar, by engagement with the ratcheted pinion 41^a on the shaft of the feed roll 50. The rock shaft 38 also carries a lower oscillating arm 43 terminating in an adjustable rod 44 connecting with a cable 45 which is the active element for imparting transverse back and forth movements to the carriage which mounts the transverse gluing mechanism and which will presently be described in detail.

The web W is fed from a roll carried by a spindle 46, the ends of which are mounted within slotted brackets 47 carried by the forward legs 25 of the frame, and the web is first guided beneath a roll 48, thence upwardly behind and over a tensioning roll 49, thence under the main feed roll 50 and over a tensioning pressure roll 51, thence forwardly around an adjusting roll 52 and forwardly over the main feed roll 50 and under pressure roller sections 53, which brings the web to the point of severance, which is effected by an oscillating shear blade 54.

The shaft of the roll 51 is carried at its ends within spring backed journal blocks 51^a (Fig. 12) slideable within guide lugs 51^b and adjustable fore and aft by spindles 51^c mounting hand wheels 51^d. Each spindle has a flat 51^e adapted to register with the inner end of an aperture in the journal block and allow the block to advance under pressure of the spring, thus putting pressure on the roll 51, but when the spindles are rotated the blocks will be retracted and the roll 51 drawn back from contact with the roll 50.

The transverse glue lines are applied to the under face of the web portion extending between the rolls 51 and 52, and by providing for the fore and aft adjustment of the roll 52 the length of the web portion between the transverse gluing line and the shear blade can be regulated in harmony with the adjustment of the feeding stroke for the web, so that each cutting stroke of the shear blade will strike the web along a line between closely adjacent glue lines, thereby permitting the severance of web sections of the desired length each having a transverse glue line closely adjacent each edge of the severed section. The transverse gluing mechanism is mounted upon a carriage 55, best illustrated in Fig. 4, which rides upon the guide rods 21 and 22 and carries a glue pot or fountain 56 partially closed on its top by a plate wall 57 having a throated aperture 58, the walls of which extend below the intended level of the glue, adhesive, or other substance to be applied to the surface of the web. The glue pot or fountain is held in position upon the carriage by a screw 59, the upper end of which is threaded into a boss 60 in the base of the glue pot, thereby permitting easy removal of the pot from the carriage.

The top plate wall 57 is provided with a flange 61 which engages an overlapping flange 62 on a closing plate 63, which flanges are locked in closed relation by the beveled inner end of a plug 64 entered through a slot 65 in the edge of the flange 62. The plug is carried by a pin 66 entered through the flange 61 and surrounded by a coil spring 67 bearing against the inner face of the flange, so that by drawing back the plug 64, which is normally countersunk in the slot 65, the closing plate can be removed from the glue pot, the closing plate having a beveled

rear edge 68 engaging an undercut flange 69 extending up from the rear wall of the glue pot.

Referring to Figs. 8 and 9, the closing plate 63 is provided near one side with depending hangers 70 each of which has entered therethrough a pointed bearing screw 71, which points in conjunction afford bearings for a pintle 72 which mounts an oscillating frame 73 open on its lower side, and having a surrounding side wall flange 74 and an overlying top wall 75 provided in its center with an aperture 76 through which project the peripheries of two companion gluing wheels 77 which are slightly spaced apart to provide parallel glue lines when brought into contact with the web. The side wall flanges 74 converge inwardly toward the pintle 72 and terminate in heads 78 which surround the pintle, which affords a hardened bearing for the oscillation of the frame.

Between the heads 78 is located a head 79 formed on the end of a center arm 80, which rocks upon the pintle as a bearing, and which in its center is provided on each side with a boss 81 within which is located a bushing 82 which affords a bearing for a short roller shaft 83 carrying the glue rolls 77 at each end.

The free end of the arm 80 is engaged on its upper side by an adjusting screw 84 entered through the upper wall of the pivoted frame 73 for adjusting the position of the frame relatively to the arm 80 which carries the glue rolls. The arm on its under side bears against a spring 85 which is supported by a bridge 86 extending across the lower portion of the oscillating frame 73. The extreme end of the arm terminates in a notched block 87 having a beveled cam face 88 adapted to be engaged by a cam block 89 on the end of an adjusting thrust rod 90 which when thrust inwardly will depress the free end of the arm 80 with the glue rolls carried thereby so as to retract the glue rolls and disable their operation as occasion may require.

The aperture 76 through which the glue rolls project is configured to afford extensions 91 the edges of which closely embrace the projecting peripheries of the respective glue rolls, and the end walls 92 of these apertures are inwardly beveled so as to afford inwardly projecting scraper edges 93 so disposed that they will alternately act as scrapers or gauges for limiting the amount of glue carried upwardly by the glue rolls as they are alternately rotated first in one direction and then in the other. By adjustment of the screw 84, the distance between these scraper edges and the peripheries of the glue rolls can be regulated to conform to the character of the glue or other substance being applied and the thickness of the coating desired.

The pivoted oscillating frame 73 is provided on its inner upper edge with an extension 94, which hooks over the adjacent edge wall of the glue pot and carries an exterior depending arm 95 which amounts a roller 96 at its lower end.

The arm 80 and associated parts are normally held elevated by the tension of a spring 97 having its lower end fastened to a pin 98 outwardly projecting from the arm 95 and its upper end secured to a screw 99 on the wall of the glue pot.

The roller 96 is positioned to roll upon the under face of a cross bar 100 mounting cam shoes 101 each carried by a slide block 102, which arrangement permits the cam shoes to be adjusted to any desired position along the cross bar 100, the arrangement being such that when

the roller 96 rides under either of the cam shoes it will be drawn down so as to depress the pivoted arm 80 carrying the glue rolls, thereby retracting the same from contact with the web, which contact will only occur while the roll is traversing the unobstructed portion of the bar 100, which is supported at its ends from hanger brackets 103.

The glue rolls act against the pressure afforded by the inverted T-shaped cross bar 23, which is provided with a facing strip 104 (Fig. 4) of soft rubber or other cushioning material which overlies the lower turn of the web at the point where the glue rolls contact the same.

The means for reciprocating the carriage will now be described: As shown in Figs. 1, 2 and 3, the carriage is shuttled back and forth by means of the endless cable 45 which is alternately moved in opposite directions by the oscillation of the arm 43. The cable passes around a lower tensioning roller 105 mounted on the end of a pivoted lever 106 the outer end of which is engaged by a spring 107 so as to impart tension on the lower part of the cable shown in Fig. 1. The two adjacent sections of the cable pass upwardly from the roller 105 and over the rollers 108 and 109 respectively in the adjacent frame rail 20, and thence inwardly and across the machine and around a roller 110 located on the opposite side.

The transversely extending turns of the cable, as best shown in Fig. 4, pass through a guide member 111 depending from the carriage, which guide member carries half cylindrical channeled guide lugs 112 so disposed as to maintain the turns of the cable against sagging below the intended plane of operation. Each of the transversely extending turns of the cable is provided with a stop block or button 113, which is of relatively small size and is normally adapted to travel freely through the space above the associated guide lug 112, as indicated at the right in Fig. 4. The guide lugs coat with a centrally pivoted rocker arm 114 provided at each end with a hooked finger 115 which, when depressed as shown at the left in Fig. 4, will obstruct the free passage of the associated stop block or button, so that the button will make engagement with the carriage and move it in the direction of movement of the associated cable turn.

As shown in Figs. 4 and 14, the rocker arm has formed therein two apertures 114^a which coat with a spring backed ball 114^b socketed within a recess in the wall of the guide member 111 and adapted to hold the rocker arm in either of its two positions of movement. The rocker arm 114 is rocked at each end of the range of movement of the carriage by trip mechanisms best illustrated in Fig. 3. Each of these trip mechanisms comprises a bell crank 116, the upper portion of which is in the form of a trip finger 117 and the lower portion in the form of a depending tail piece 118. Each bell crank is carried by a pivot 119 located at the inner end of a bracket arm 120 projecting inwardly from the proximate side frame rail of the machine, the arrangement being duplicated as shown.

The trip finger 117 is normally elevated by the pull of a spring 121, and the trip finger normally stands in position to overlie and strike down the proximate end of the rocker arm 114 when the carriage is moved to the end of its operating range. As shown in Fig. 3, one of the trip mechanisms is positioned to act upon one end of the rocker arm, and the companion trip

mechanism on the opposite side of the machine is positioned to act upon the other end of the rocker arm. Each trip mechanism is positioned to coat with one of the two turns of the cable 45 and with the block or button 113 carried thereby.

With the trip finger normally elevated as shown at the right in Fig. 3, and with the button 113 moving to the right, and with the near end of the rocker arm elevated as in Fig. 4, the button will travel freely through the space above the channeled lug 112 until it strikes under the tail 118 on the trip member, which momentarily kicks down the trip finger 117 and depresses the near hooked end of the rocker arm, so that on the return movement of the button to the left it will engage the outer side of the depressed rocker arm finger and carry back the carriage with it to the left hand position indicated in dotted lines in Fig. 3. The carriage will then stand in the left hand position until the button on the far turn of the cable performs a similar tripping operation in preparation for the shutting back of the carriage to the right. These shuttling operations are properly timed to impart the back and forth carriage movements during the intervals of rest in advance of the web, so that the glue lines will be applied during such intervals.

The mechanism for adjusting the roll 52 will now be described: The roll is carried upon a spindle 122 (Fig. 3) having at each end a roller 123, the right hand roller being journaled within a slide block 124 through which is entered an adjusting screw 125 having at its forward end a hand wheel 126. At each end of the spindle is a spur gear 127 meshing with an overhead rack 128, so that by operating the hand wheel the slide block can be adjusted with relation to the gauge plate 128^a, and the intermeshing of the gears with the racks at opposite ends of the roll 52 will maintain equality in the adjustment at each end and prevent binding or cramping.

The roll 50, as shown in Fig. 2, is grooved to receive stripper fingers 128^b which prevent the leading edge of the web from passing down around the roll; and the roll 50 underlies and coats with the pressure roller sections 53, best shown in Fig. 3. These roller sections are mounted upon a shaft 129, and each roller section consists of a group of grooved members 130 which are adapted to be adjusted transversely by the engagement of fins 131 depending from a rider 132 mounted upon a cross rod 133 and adapted to be held in adjusted position by a thumb screw 134, the arrangement being such as to permit the grooved roller sections to be so positioned as to afford clearance for the longitudinal glue lines and spaced sufficiently far apart to allow the transverse glue lines to pass between the roller sections without being contacted thereby.

The lower edges of the fins 131 lie closely adjacent to the upper surface of the advancing web and terminate at a point closely adjacent the edge of the movable shear blade 54 which coats with a fixed shear blade 135 located below the web, as shown in Fig. 4. The movable shear blade is pivoted at one end and actuated by suitable connections with the driving train at regularly timed intervals, so that at each descent of the shear blade the web will be severed and the severed section carried forward upon an endless carrier 136 (Fig. 1).

The longitudinal glue lines are applied to the

under surface of the web by means of one or more gluing rollers 137 each journaled within a glue pot 138 provided with a bracket 139 terminating in a grooved head 140 which bears against a hexagonal rock shaft 141 and is held in place by an L-shaped locking bar 142 pivoted to the bracket 139 and having a locking screw 143 entered through its lower end and into a lug 144 depending from the bracket, so that by tightening up the screw the glue pot will be locked upon the hexagonal rock shaft in the desired position, it being understood that a plurality of such glue pots may be employed.

The rock shaft 141 carries an obliquely disposed arm 145 having at its end a pivoted dog 146 adapted to be engaged by a block 147 adjustably mounted upon a segment 148 carried by an arm 149 fixedly secured to the rock shaft 38, the arrangement being such that with each downward oscillation of the block 147 the dog 146 will be engaged and rocked during the period of engagement, which may be varied by adjusting the block to the desired position. This rocks the shaft 141 and elevates the glue pot and roller into contact with the web to apply a longitudinal glue line of the desired length, depending upon the period of engagement of the block with the dog.

In Fig. 11 I have shown a modified form of mechanism for oscillating the rock shaft 141 which carries the glue pot or pots 138. In this instance the rock shaft is provided on its end with a segmental plate 150 having an arcuate slot 151 which receives an adjustable pivot 152 at the upper end of a link 153, the lower end of which is pivoted to the short arm of a lever 154, the opposite end of which rides upon a cam disk 155 having a high side 156.

The cam disk is provided with arcuate slots 157 which receive locking pins 158 carried by cam segments 159 each of which has a cam face 160 registering with the high side of the cam disk and of the same concentric curvature, so that by adjusting the segments the effective lengths of the high cam surface can be increased or diminished to any desired degree, thereby permitting adjustment of the period during which the glue rollers will be elevated to contact the surface of the web. The cam disk and segmental plates are carried by a shaft 161 having thereon a sprocket wheel 162 driven by a sprocket chain 163 carried around a sprocket 164 on the shaft which carries the gear 35 of the reducing train.

Operation

In operation the various mechanisms are driven in timed relation by the motor 30 operating through the reducing gear mechanism which imparts regularly timed oscillations to the rock shaft 38. The shaft actuates the upper oscillating bar 39 and the rack bar 41, so that, at each upward thrust of the rack bar, rotation will be imparted through the ratcheted gear 41a to the main feed roll 50. The length of the feeding stroke can be varied within wide limits by the adjustment of the head 42 on the oscillating bar, and accuracy of this adjustment is required in order to measure off and sever web strips of the desired length. Immediately after the feeding movement of the roll 50, and while the web is at rest, the movable shear blade will descend and cut off a web section of the intended length.

During the forward advance of the web and while the rock shaft 38 is moving in a counter-clockwise direction, the block 147 carried by the segment 148 will engage the dog 146 and impart

an oscillating movement of the rock shaft 141 which carries one or more glue pots 138, which will thus be elevated to bring the longitudinal gluing rollers into contact with the under face 5 of the web at the point where it passes under the roll 50. The interval during which the gluing contact will occur may be regulated by the adjustment of the block 147, so that a longitudinal glue line or lines of the desired length will be applied to the web. During the interval of rest, duplicate transverse glue lines will be applied to the web at the point where it is backed by the rubber facing strip on the under side of the inverted T-shaped bar 23.

The back and forth movements of the transverse glue carriage 55 will be regularly effected by the cable and trip mechanism in the manner previously described, and the range of these carriage movements will be uniform during each 10 cycle of operations; but the length of the gluing contact may be regulated by the adjustment and spacing of the cam shoes 101, since the transverse gluing rollers will be held depressed away from the web during the intervals of time while the roller 96 rides upon the cam shoes, and the gluing will occur only when the roller is permitted to elevate sufficiently to engage the under surface of the bar 100. It is thus possible to apply the duplicate transverse glue lines at any desired position transversely of the web and to regulate the length of the lines as desired.

By adjusting the roll 52, through the operation of the hand wheel 126, to proper position in relation to the gauge plate, the length of web between 35 the point of application of the glue lines and the line of severance by the blade can be exactly computed, and since the shear blade operates at regular recurrent intervals it is necessary that the length of web thus measured off shall either 40 be equal to or an exact multiple of the length of web advanced by the feeding stroke imparted through the rack 41 to the feed roll 50.

By maintaining a proper relationship between the adjustment of the web feeding stroke and the 45 length of the web section between the gluing lines and the line of severance, it is possible to insure precision in the cutting of the web sections which in each instance must be severed along a line intermediate the closely spaced parallel transverse 50 glue lines, so that each severed section will have a glue line along each of its edges, which glue lines will extend transversely of the grain of the web.

Although both the longitudinal and transverse 55 glue lines are applied to a downwardly presented turn of the web surface, these glue lines will be presented on the upper surface of the web turn as it advances toward the pressure roll sections 53, but by properly adjusting the grooves in said roll sections to straddle the glue lines, the danger 60 of smearing will be avoided.

The method of actuating the transverse glue carriage is one which insures the application of glue lines on each forward movement and each 65 return movement of the carriage and a proper timing of these movements with relation to the intermittent feeding of the web, with proper intervals of rest for the carriage while the web is being advanced.

Although throughout the specification I have referred to the application of glue, it will be understood that this is intended to cover the application of any desired form of adherent or other liquid to a web, whether for gluing purposes or otherwise, and that it is not the intention to lim-

It the use of the machine solely to the application of glue.

Although the invention has been described in full detail, it will be understood that numerous changes or modifications in structure can be made without departing from the spirit of the invention.

I claim:

1. In a machine of the class described, the combination of means for intermittently advancing a predetermined length of web, a glue pot mounted for reciprocation back and forth with relation to the web, gluing devices carried by the glue pot and mounted therein for movements toward and from the web, a cam track adjacent said gluing devices, and a member connected with said gluing devices and adapted to ride upon said cam track and to be moved thereby to impart movements of said gluing devices toward and from the web, and means for imparting back and forth movements to the glue pot and gluing devices at timed intervals to effect the application of a glue line during each forward and each return movement of the glue pot, said means including a reciprocating cable carrying contact blocks each adapted when engaged with the glue pot to impart movements thereto, and trip members for alternately causing the respective contact blocks to effect engagement with the glue pot.

2. In a machine of the class described, the combination of means for advancing a web, carriage mechanism including a glue pot and gluing means, said gluing means being adapted to be moved toward and from the web, and means for effecting such movements, a reciprocable cable having forward and reverse turns extending in parallel relation to the line of movement of the carriage mechanism, each turn of the cable being provided with a contact block, a movable device on the carriage mechanism adapted to be alternately engaged by each of said contact blocks when moving in one direction and to permit clearance of each of said blocks when moved in the opposite direction, and trip means for actuating said movable device to permit said contact blocks to alternately effect operative engagement with said carriage mechanism.

3. In a machine of the class described, the combination of means for advancing a web, carriage mechanism mounted for back and forth movements with relation to the web and including a glue pot and gluing devices carried thereby, means for alternately moving the gluing devices toward and from the web during the movements of the carriage mechanism, and a reciprocating cable having forward and reverse turns each carrying a contact block movable to alternately engage the carriage mechanism and impart movements thereto, a movable device on the carriage mechanism adapted when in one position to permit clearance of one of the contact blocks and to effect engagement with the other contact block, and when in the opposite position to reverse the clearance and engagement of the respective contact blocks, and trip means for reversing the position of said movable device at the terminus of the carriage movement in each direction.

4. In a machine of the class described, the combination of means for advancing a web, carriage mechanism including a glue pot and gluing devices and mounted for back and forth movements with relation to the web, means adjacent the line of movement of the carriage mechanism for imparting to the gluing devices movements

toward and from the web during each traverse of the carriage mechanism, a reciprocable cable presenting forward and reverse turns in adjacent relation to the line of movement of the carriage, each of said turns having a contact block mounted thereon, a rocking bar pivoted to the carriage and having a hook at each end so positioned as to permit alternate engagement of the cable turns as the rocking bar is actuated, the retracted end of the rocking bar affording a clearance for the passage of the associated contact block, and trip members at opposite ends of the range of movement of the carriage mechanism and adapted each to rock the rocking bar in a different direction to effect alternate engagement by each of the contact blocks with the associated end of the rocking bar to impart movement thereto from the respective cable turns to the carriage mechanism.

5. In a machine of the class described, the combination of means for intermittently advancing a web section of predetermined length, said means including a roll adjustable toward and from the intended line of severance of the web, cutting means for effecting a cut along said line of severance, gluing means adapted to move transversely of the web along a line behind said adjustable roll, and means for adjusting the length of web advanced during each feeding movement with relation to the adjustment of said roll to effect a cutting of the web along a line having predetermined relation to the glue line applied to the web.

6. In a machine of the class described, the combination of means for guiding a web and forwardly feeding the same intermittently, cutting means for severing the web at uniformly recurrent intervals, reciprocal gluing means adapted to apply transverse glue lines to the web, the web guiding means including a roll interposed between the line of application of the glue and the line of severance and adjustable to vary the length of the web between the glue line and the line of severance, and means for adjusting the length of the web fed forward during each feeding operation with relation to the adjustment of said roll to insure the cutting of the web along lines having definite relation to the glue lines applied to the web.

7. In a machine for applying glue to a web, the combination of a glue pot mounted for reciprocation back and forth with relation to the web, gluing devices carried by the glue pot and mounted therein for movements toward and from the web, a cam track adjacent said gluing devices, and a member connected with said gluing devices and adapted to ride upon said cam track and to be moved thereby to impart movements of said gluing devices toward and from the web, and means for imparting back and forth movements to the glue pot and gluing devices at timed intervals to effect the application of a glue line during each forward and each return movement of the glue pot, said means including a reciprocating cable carrying contact blocks each adapted when engaged with the glue pot to impart movements thereto, and trip members for alternately causing the respective contact blocks to effect engagement with the glue pot.

8. In a machine for applying glue to a web, the combination of a carriage mechanism including a glue pot and gluing means, said gluing means being adapted to be moved toward and from the web, and means for effecting such movements, a reciprocal cable having forward

and reverse turns extending in parallel relation to the line of movement of the carriage mechanism, each turn of the cable being provided with a contact block, a movable device on the carriage mechanism adapted to be alternately engaged by each of said contact blocks when moved in one direction and to permit clearance of each of said blocks when moved in the opposite direction, and trip means for actuating said movable device to permit said contact blocks to alternately effect operative engagement with said carriage mechanism.

9. In a machine for applying glue to a web, the combination of a carriage mechanism mounted for back and forth movements with relation to the web and including a glue pot and gluing devices carried thereby, means for alternately moving the gluing devices toward and from the web during the movements of the carriage mechanism, and a reciprocating cable having forward and reverse turns each carrying a contact block movable to alternately engage the carriage mechanism and impart movements thereto, a movable device on the carriage mechanism adapted when in one position to permit clearance of one of the contact blocks and to effect engagement with the other contact block, and when in the opposite position to reverse the clearance and engagement of the respective contact blocks, and trip means for reversing the position of said movable device at the terminus of the carriage movement in each direction.

10. In a machine for applying glue to a web, the combination of a carriage mechanism including a glue pot and gluing devices and mounted for back and forth movements with relation to the web, means adjacent the line of movement of the carriage mechanism for imparting to the gluing devices movements toward and from the web during each transverse of the carriage mechanism, a reciprocable cable presenting forward and reverse turns in adjacent relation to the line of movement of the carriage, each of said turns having a contact block mounted thereon, a rocking bar pivoted to the carriage and having a hook at each end so positioned as to permit alternate engagement of the cable turns as the rocking bar is actuated, the retracted end of the rocking bar affording a clearance for the passage of the associated contact block, and trip members at opposite ends of the range of movement of the carriage mechanism and adapted each to rock the rocking bar in a different direction to effect alternate engagement by each of the contact blocks with the associated end of the rocking bar to impart movement thereto from the respective cable turns to the carriage mechanism.

11. In a machine of the class described, the combination of means for advancing a web, cutting means for recurrently severing said web into sections, gluing means adapted to move transversely of the web to apply a glue line thereto prior to its arrival at the line of severance, and means for adjusting the length of the web between the point of application of the glue line and the point of severance to effect a cutting of the web along a line having predetermined relation to the glue line applied to the web.

12. In a machine of the class described, the combination of means for intermittently advancing a web section of predetermined length during each intermittent operation, cutting means for effecting a cut across the web during a pause in the advancement of the web, gluing means

adapted to move transversely of the web prior to its arrival at the cutting line, and means for adjusting the length of web intervening between the line of application of the glue and the cutting line to effect a cutting of the web along a line having predetermined relation to the glue line applied to the web.

13. In a machine of the class described, the combination of means for advancing a web, means for applying a longitudinal glue line to the under surface of the web in parallel relation to the direction of advancement, including a glue pot having a gluing device carried thereby, a rock shaft upon which the glue pot is carried, and means for rocking said shaft to bring the gluing device recurrently into contact with the surface of the advancing web.

14. In a machine of the class described, the combination of means for advancing a web, means for applying a longitudinal glue line to the under surface of the web in parallel relation to the direction of advancement, including a glue pot having a gluing device carried thereby, a rock shaft upon which the glue pot is carried, cam mechanism having an adjustable cam surface for varying the period of the operations effected by the cam mechanism, and connections between said rock shaft and said cam mechanism to rock the shaft to bring the gluing device recurrently into contact with the web during a period of advancement determined by the adjustment of the cam mechanism.

15. In a machine of the class described, the combination of means for intermittently advancing a predetermined length of web, a glue pot located below the web and mounted for reciprocation transversely back and forth at a fixed distance below the web, gluing devices carried by the glue pot and mounted therein for movements toward and from the web and adapted when elevated to apply a glue line to the under surface of said web, elevating means for said gluing devices carried in part by the glue pot and in part by a stationary portion of the machine for imparting movements to the gluing devices during a predetermined portion of the movements of the glue pot to impart glue lines to the under surface of the web, and means for imparting back and forth movements to the glue pot and gluing devices at timed intervals to effect the application of a glue line during at least one of said forward and return movements of the glue pot.

16. In a machine of the class described, the combination of means for intermittently advancing a predetermined length of web, a glue pot located below the web and mounted for reciprocation transversely back and forth at a fixed distance below the web, a glue roller carried by the glue pot and mounted therein for movements toward and from the web and adapted when elevated to apply a glue line to the under surface of said web, elevating means for said glue roller carried in part by the glue pot and in part by a stationary portion of the machine for imparting movements to the glue roller during a predetermined portion of the movements of the glue pot to impart glue lines to the under surface of the web, and means for imparting back and forth movements to the glue pot and glue roller at timed intervals to effect the application of a glue line during at least one of said forward and return movements of the glue pot.
